CASING PROTECTOR

James F. Medearis, Ventura, Calif.

Application September 18, 1948, Serial No. 49,971

6 Claims. (Cl. 308—4)

1

This invention relates to oil well drilling equipment and particularly pertains to a casing protector.

In the drilling of oil wells it is common practice to place non-metallic rings or sleeve sections upon the drill string at intervals therealong so that these members will act to protect the casing through which the drill string extends and within which it rotates. This protection is considered desirable due to the fact that the well bore is not always straight, thus making it possible for the drill string to rub against the casing and to wear the casing as well as the drill string. It may also occur that the drill string will tend to whip in the well and to thus violently strike against the casing through which it extends and through which it rotates. Rubber casing protectors have therefore been provided for this purpose since they can be made with a continuous tubular wall and can be stretched to pass over the relatively large tool joints occurring at opposite ends of a length of drill string and then contract onto the main body of the drill string. In actual practice an attempt is made to position a series of protecting rings at points along a length of drill pipe so that uniform protection will be afforded for the casing. The protecting rings, however, have a tendency to slide along the lengths of drill pipe so that they do not give effective protecting action. Attempts have been made to correct this defect by strengthening the rubber rings so that they will exert greater contractive force around the drill pipe, but this gives an added problem due to the fact that greater force is necessary to stretch the rings and to cause them to pass over the enlarged tool joints at the ends of the drill pipe sections. This stretching action not only requires enormous force but it has a tendency to impair the contractive qualities of the rings so that they will not grip the reduced diameter of the drill pipe with sufficient strength to retain their positions therealong. It is desirable, therefore, to provide a casing protector which may be applied directly to the body of the drill string and will hold firmly in position. It is the principal object of the present invention to provide a casing protector ring or sleeve which is longitudinally split and is fitted with means whereby it may be drawn tight around the body of a drill pipe and latched in a manner to hold it under tension and without impairing its elastic qualities.

The present invention contemplates the provision of a casing protector ring which is longitudinally split and along the contiguous edges of

2

the split mechanical fastening means are provided to be interlocked and to hold the body of the ring under tension in its embracing position around the pipe.

5 The invention is illustrated by way of example in the accompanying drawings in which:

Figure 1 is a view in side elevation showing the casing ring with which the present invention is concerned and indicating it as being mounted upon a fragmentary length of drill pipe.

10 Fig. 2 is a view in transverse section through the ring as seen on the line 2—2 of Fig. 1 and shows the ring in its locked position.

Fig. 3 is a view in perspective showing the 15 latch plates of the ring dissociated from the body of the protector.

Fig. 4 is a view in transverse section showing another form of the protector ring, the contiguous edges of which are secured together by a pin.

20 Referring more particularly to the drawings, 10 indicates a drill pipe upon which a casing protector 11 is mounted. This casing protector has a cylindrical tubular wall 12 which is formed of a deformable and flexible material such as rubber and is longitudinally split, as indicated at 13 in Fig. 2. It is preferable that the line of severance shall have an outer portion 14 disposed radially with relation to the axis of the pipe and an inner portion 15 which is disposed obliquely to the plane of the radial portion 14. This provides an angular toe 16 which fits under an overlapping shoulder 17 so that the protector will tend to be wrapped around the pipe 10. Imbedded in the wall 12 of the protector and having 25 portions extending toward each other and across the portion 15 of the longitudinal parting line 13 are interlocking plates 18 and 19. These plates are preferably of a length shorter than the overall length of the sleeve so that full resilient end portions of the sleeve will embrace the pipe. These plates, as shown in Fig. 3, are arcuate in shape and at their contiguous edges are formed with hooks 20 and 21, respectively. The hooks lie within recesses 22 and 23 formed in the wall 12 of the protector to permit them to move into 30 interlocking relation with each other. The walls of said recesses are inclined so that the hooks 20 and 21 will be yieldably urged into their locked position. The body portions of the members 18 and 19 are imbedded within the rubber of the wall 12 and are formed with a plurality of perforations 24 through which the rubber may make a bond. Equally spaced throughout the length of each of the plates 18 and 19 are installation 35 perforations 25 which communicate with holes

40 45 50 55 60 65 70 75 80 85 90 95 100

26 extending radially and formed through the outer section of the protector wall 12 to terminate within portions 26' formed in the inner sections of the wall 12 so that a prong-like member may pass inwardly through the holes 26 and the perforations 25 in the plates to draw the protector around the pipe 10 and to bring the hook edges 20 and 21 into interlocking relation with each other, as shown in Fig. 2.

In the form of the invention shown in Fig. 4 the plates 18 and 19 are formed with loops 27 which intermesh with each other along the contiguous edges of the plates 18 and 19 and receive a lock pin 28. Attention is directed to the fact that in either form of the invention shown there will be an articulate connection between the contiguous edges of the plates 18 and 19 so that the body of the sleeve will be free to flex and so that the portion of the sleeve occurring on the outside of the plates 18 and 19 will have sufficient resiliency to function as a non-metallic protector.

In operation of the present invention the protecting rings are made as shown in the drawings and are formed with an inner diameter which is normally less than the outer diameter of the drill pipe 10. This inner diameter has been calculated with relation to the formula used in making rubber for the sleeve so that when the sleeve is in an embracing position around the pipe there will be sufficient tension in the rubber to hold the protecting ring in position on the pipe and to grip it with sufficient force to prevent it from slipping longitudinally of the pipe. After the ring has been thus constructed it is applied to the pipe by spreading the longitudinal split side of the ring open so that it will pass around the pipe. A suitable tool carrying prongs is then positioned with the prongs in the openings 26 and 26' of the ring and through the perforations 25 in the plates 18 and 19. The prongs are then forcibly drawn together to cause the edges of the hook portions 20 and 21 to overlap and move into a hooked relation to each other. The pressure on the prongs is then released and the expansive force exerted by the rubber will act to hold the hooks in their interengaged position and hold the ring in gripping relation to the pipe. Attention is directed to the fact that due to the formation of the toe 16 and the shoulder 17 the wall of the ring 14 tends to wrap around the pipe 10 so that there will not be a continuous break in the wall throughout a radial plane and so that the overlapping portion of the ring along the line 15 will add additional frictional resistance to displacement of the ring on the pipe. It will also be evident that due to the fact that the line of severance forms radial portions 14, these portions will be drawn against each other in a firmly abutting relation so that the plates 18 and 19 will be retained under tension and the hooked edges 20 and 21 will be held in firm engagement.

It will thus be seen that the protecting sleeve here shown is simple in construction and presents a continuous cylindrical resilient surface for contact with the casing, said sleeve being so designed as to be placed upon the drill pipe without passing over the tool joint and so that it may be locked and firmly held in position due to the inherent resiliency of the sleeve wall.

While I have shown the preferred form of my invention as now known to me, it will be understood that various changes may be made in combination, construction and arrangement of parts by those skilled in the art, without departing from the spirit of the invention as claimed.

Having thus described my invention, what I claim and desire to secure by Letters Patent is:

1. A casing protector comprising a rubber sleeve having a cylindrical wall which has a single longitudinal split extending the full length thereof said split forming confronting edge faces whereby, when the sleeve is positioned around a drill pipe and stretched into gripping relation therewith, the edge faces formed by said split may be brought into abutting relation, independent arcuate metal anchor plates embedded within edge portions of said wall adjacent said split and bonded to the rubber of said sleeve, and complementary metal hooks formed on outer edges of said plates and extending out of said edge faces, there being recesses formed in said edge faces which are located to respectively receive said hooks when said sleeve is stretched about a drill pipe as aforesaid, said hooks thereby being brought into overlapping relation, whereupon, when released, said hooks interlock to retain said sleeve stretched tightly about said drill pipe, said cylindrical wall and the plates embedded therein being provided with radial holes opening outwardly for the reception of sleeve engaging elements of a tool for constricting said sleeve about a drill pipe to effect the application of said sleeve thereto or the removal of said sleeve therefrom.

2. A casing protector comprising a rubber sleeve having a cylindrical wall which has a single longitudinal split extending the full length thereof said split forming confronting edge faces whereby, when the sleeve is positioned around a drill pipe and stretched into gripping relation therewith, the edge faces formed by said split may be pressed together in abutting relation, independent arcuate metal anchor plates embedded within edge portions of said wall adjacent said split and bonded to the rubber of said sleeve, and complementary metal hooks formed on outer edges of said plates and extending out of said edge faces, complementary inner portions of said edge faces lying obliquely with relation to a radial plane containing the axis of said sleeve and the center line of said split, there being recesses formed in said edge faces which are located to respectively receive said hooks when said sleeve is stretched about a drill pipe as aforesaid and said edge faces compressed together so as to deform the same, said hooks thereby being brought into overlapping relation whereupon, when released, said hooks interlock to retain said sleeve stretched tightly about said drill pipe and holding said edge faces in compressed abutting relation.

3. A combination as in claim 2 in which complementary outer portions of said abutting edge faces are angled relative to said inner portions.

4. A combination as in claim 3 in which said cylindrical wall and the plates embedded therein are provided with radial holes opening outwardly for the reception of sleeve engaging elements of a tool for constricting said sleeve about a drill pipe to effect the application of said sleeve thereto or the removal of said sleeve therefrom.

5. A casing protector comprising a rubber sleeve having a cylindrical wall which has a single longitudinal split extending the full length thereof, said split forming confronting edge faces whereby the sleeve may be positioned around a drill pipe and stretched into gripping encircling relation therewith, arcuate anchor plates embedded within edge portions of said wall adjacent said split and bonded to the rubber of said sleeve, and matching connecting means formed on outer edge portions of said plates which means are adapted

to be interlocked, when said sleeve is stretched about a drill pipe as aforesaid, said connecting means when interlocked, retaining said sleeve stretched tightly about said drill pipe, outwardly opening radial holes being formed in said cylindrical wall and the plates embedded therein, for reception of sleeve engaging elements of a tool for constricting said sleeve about said drill pipe to effect the application of said sleeve thereto or its removal therefrom.

6. A casing protector comprising a rubber sleeve having a cylindrical wall which has a single longitudinal split extending the full length thereof, said split forming confronting edge faces whereby, when the sleeve is positioned around a drill pipe and stretched into gripping relation therewith, the edge faces formed by said split may be pressed together in abutting relation, independent arcuate metal anchor plates embedded within edge portions of said wall adjacent said split and bonded to the rubber of said sleeve, and complementary metal hooks formed on outer edges of said plates and extending out of said edge faces, there being recesses formed in said edge faces which are located to respectively receive said hooks when said sleeve is stretched about a drill pipe as aforesaid

15

20

25

and said edge faces compressed together so as to deform the same, said hooks thereby being brought into overlapping relation whereupon, when released, said hooks interlock to retain said sleeve stretched tightly about said drill pipe and hold said edge faces in compressed abutting position, said cylindrical wall and the plates embedded therein being provided with radial holes opening outwardly for the reception of sleeve engaging elements of a tool for constricting said sleeve about a drill pipe to effect the application of said sleeve thereto or the removal of said sleeve therefrom.
